UNITED STATES PATENT OFFICE.

ROBERT HAY ROBERTSON, OF DUNFERMLINE, SCOTLAND, ASSIGNOR TO SEARS, ROEBUCK & CO., OF CHICAGO, ILLINOIS, A CORPORATION OF ILLINOIS.

DESIGN FOR A TABLECLOTH.

Application filed December 17, 1926, Serial No. 20,064, and in Great Britain September 1, 1926. Term of patent 14 years.

To all whom it may concern:

Be it known that I, ROBERT HAY ROBERTSON, a subject of the King of Great Britain, residing at Dunfermline, in the county of Fife, Scotland, have invented a new, original, and ornamental Design for a Tablecloth, of which the following is a specification, reference being had to the accompanying drawing, forming part thereof.

The figure is a plan view of a tablecloth showing my new design.

I claim:

The ornamental design for a tablecloth as shown.

ROBERT HAY ROBERTSON.
